DESIGN FOR A SKIRT AND JACKET ENSEMBLE

Claire Smith Golden, Hempstead, N. Y.

Application April 3, 1942, Serial No. 106,451

Term of patent 3½ years

To all whom it may concern:

Be it known that I, Claire Smith Golden, a citizen of the United States of America, residing in Hempstead, county of Nassau, and State of New York, have invented a new, original, and ornamental Design for a Skirt and Jacket Ensemble, of which the following is a specification, reference being had to the accompanying drawing, forming part thereof.

Fig. 1 is a front view of a skirt and jacket ensemble showing my new design.

Fig. 2 is a rear view thereof.

Fig. 3 is a fragmentary front view of the skirt portion.

Fig. 4 is a rear view of Figure 3.

I claim:

The ornamental design for a skirt and jacket ensemble, substantially as shown.

CLAIRES SMITH GOLDEN.
